UNITED STATES PATENT OFFICE

FERDINAND W. MOSTERTZ, OF PHILADELPHIA, PENNSYLVANIA

FILE FABRIC AND METHOD OF WEAVING SAME

Application filed July 10, 1931. Serial No. 549,980.

The present invention relates to an improved pile fabric and the method of weaving the same, particularly with an uncut pile. The fabric so shown is made in many 5 different ways, but this particular type of fabric, as the invention, has for its purpose to provide a method of weaving, which will make considerably more production than is known by the older methods.

10 A very important idea in this improved method is the use of upper and lower shuttles, certain picks being inserted by the upper shuttles, while certain other picks are inserted by the lower shuttles, the upper 15 shots being used for making the pile loops, which are formed by two separate groups of threads.

20 The old and known methods of weaving the character of fabric as described and illustrated herein are set forth in a German Patent Number 78,192 and also in a United States Letters Patent Number 1,382,516, but in the methods in these patents only one shot or filling is thrown at a time in the following 25 manner:

"Shot one from left to right, shot three from right to left, and shot four from left to right, etc."

Another purpose of this invention is to 30 avoid such methods as in the German and United States patents above identified, and to accomplish this, as previously stated it is the aim to utilize two shuttles simultaneously in conjunction with a double shed system.

35 It is to be understood that the particulars herein given are in no way limitative, and that while still keeping within the scope of the invention, any desired modification of details and proportions may be made in the construction of the appliance according to 40 circumstances.

The invention comprises further features and combination of parts to be hereinafter 45 set forth, shown in the drawing and claimed.

In the drawing:—

Figure 1 is a cross section view through a piece of pile fabric with an uncut pile showing the elimination of the pile gauge.

Figure 2 is a cross sectional view through the same character of fabric, but showing 50 the use of the pile gauge.

Figure 3 is a sectional view through a piece of fabric also illustrating the elimination of the pile gauge, and showing the loose floating filling threads 2 removed.

Figure 4 is a diagram showing the method of the shots and the use of the upper and lower shuttles, with the double shed system.

Figure 5 is a detail perspective diagram 60 showing the direction of filling of weft threads or picks.

Referring to the drawing and especially Figure 1, 1 and 2 identify the ground warp threads, while 4 identifies the pile warp thread, which when the piece of fabric is complete is uncut. The ground warp threads 1 and 2 pass under and over the filling or weft threads 5, which are shot by the lower shuttle; said ground warp threads in 70 passing over and under the filling or weft threads cross at points between the filling or warp threads.

The pile warp threads 4 pass under every other one of the filling or weft threads 5, and then over every other one of the upper filling or weft threads 6. Where the pile warp threads pass over the upper filling or weft threads 6 alternate with the passing of the same threads under the filling or weft threads 5. In weaving this type of fabric the upper filling or weft threads are shot by the upper shuttle. Every other one of the upper filling or weft threads 6a are loose and floating, and therefore can be removed when the fabric is completed, as in Figure 3. In Figure 1 the pile loops formed by the pile warp threads 4 are formed around or over certain of the filling or weft threads 6, as 80 previously stated, and are consequently only 85 90

as high as the thickness of the filling threads permit.

Referring to Figure 2 it will be noted that the upper and lower filling or weft threads have a supporting warp or pile gauge 7 separating them, for the purpose of increasing the height of the pile loops of the pile warp threads.

Referring to Figure 4 it is obvious that 10 the upper and lower shuttles 8 and 9 operate simultaneously, and for such a purpose a double shed system may be applied, of which Figure 4 is an illustration, illustrating the ground warp threads 1 and 2 and the pile 15 warp thread 4. Also referring to Figure 4 it will be noted that a roof 10 is fastened to a reed 11 for the purpose of preventing the upper shuttle 8 from flying out when the loose 20 floating filling or weft thread or pick 6a is shot. The shuttles 8 and 9 are shot simultaneously, the lower shuttle 9 through the bottom shed, the upper shuttle 8 through the upper shed inserting pick or lower filling or weft thread 5 and the upper filling or weft 25 thread or picks 6, these operations being performed simultaneously when going over one way, and then inserting the alternate filling or weft threads or picks simultaneously when coming back.

30 The invention having been set forth, what is claimed is:

1. A single piece of frise unfinished fabric having an uncut pile, said fabric comprising upper and lower filling or weft threads, 35 alternate upper filling or weft threads being floating and removable, ground warp threads being arranged to tie in the lower filling or weft threads, and pile loop warp threads being engaged under every other one of the lower 40 filling or weft threads and over the upper filling or weft threads alternately with relation to the removable floating filling weft threads, said upper and lower filling or weft threads adapted to receive pile gauges there- 45 between, which are removable and thereby form uncut pile loops.

2. In a method of weaving a single piece of unfinished frise uncut pile fabric with longitudinal pile gauges forming pile loops, 50 the steps consisting in throwing simultaneously upper and lower shuttles of a double shuttle loom with wefts, alternate upper ones of which being loose or floating the lower shuttle for the lower layer of filling or ground 55 weave, the upper shuttle for the upper layer of filling or the so called loop or frise shot, weaving ground warp threads over and under the lower tier of filling or weft threads, weaving an uncut pile warp under alternate 60 weft threads of the lower tier.

3. In a method for weaving a single piece of frise uncut pile fabric with longitudinal pile gauges for forming pile loops, the steps 65 consisting in throwing simultaneously upper and lower shuttles of a double shuttle

loom with wefts, alternate upper ones of which being loose or floating, the lower shuttle for the lower layer of filling or ground weave, the upper shuttle for the upper layer of filling or so called loop or frise shot, weaving ground warp threads over and under a lower tier of filling or weft threads, weaving an uncut pile warp under certain of the filling or weft threads, and then removing said alternate loose or floating weft threads.

In testimony whereof I affix my signature.

FERDINAND W. MOSTERTZ.
